Filed Aug. 30, 1963, Ser. No. 76,419

Term of patent 3½ years

(Cl. D54—1)

FIG. 1 is a side elevational view of a bracket for attaching the container of an insecticide applicator to a grain conveying tube, showing our new design;

FIG. 2 is an elevational view showing one end thereof;

FIG. 3 is an elevational view showing the opposite end; and

FIG. 4 is a top plan view of bracket for attaching the container of an insecticide applicator to a grain conveying tube.

The broken line showing of the container, tubes, and attaching elements in FIG. 1 are disclosed for illustrative purposes only.

We claim:

The ornamental design for a bracket for attaching the container of an insecticide applicator to a grain conveying tube, as shown and described.
